REVERSIBLE SEAT

Edward Bunker, Tarpon Springs, Fla., assignor to
 Coach & Car Equipment Corporation, Chicago,
 Ill., a corporation of Illinois

Continuation of application Serial No. 512,692,
 December 3, 1943. This application October 29,
 1946, Serial No. 706,489

5 Claims. (Cl. 155—96)

1

This invention relates to improvements in revoluble seat structures suitable for use in railway passenger cars and similar situations where it is desirable to arrange one side of the seat in close relation to a side wall of the car and to reverse the seat from time to time so that it will normally face in either of two directions.

The revoluble seats heretofore used have included manually operable locking means for holding the revoluble portion of the seat in either of its two operating positions. Such locking means usually include foot operated levers or other devices operated independently of the movement of the seat. Such locking devices, therefore, add to the cost of manufacture of the seat structure and are otherwise unsatisfactory since they require service from time to time to replace broken and worn parts and, due to their position near the floor level, interfere with the cleaning of the floor.

A principal object of the present invention is to provide an improved revoluble seat structure in which the revoluble portion of the seat will automatically be locked in or released from its normal operative positions by the movement of the seat to and from said positions.

A further and more specific object is to provide, in a seat structure of the above general class, a means providing a movable locking connection between the revoluble portion of the seat and a fixed base whereby the revoluble portion of the seat is held firmly in position against any forces tending to tilt it relative to the base and whereby application of pressure against the front and back portions of the seat will not release it from its normal operative positions.

The invention, briefly described, includes the provision of a seat portion supported on a fixed base with capacity for combined lateral and revoluble movements, whereby the seat may be normally positioned in close relation to the wall, but may be moved outwardly therefrom to provide the necessary clearance to permit the seat to be reversed by rotating it about its vertical axis.

The combined movements of the seat portion are caused to follow a predetermined path by means of a pair of link members operating in a horizontal plane and connecting the movable seat with the base. A horizontal web portion of the base is formed with an opening, the edges of which have a contour corresponding to the path of movement of the revoluble seat portion. The edges of said opening cooperate with a stud, carried by the seat and connecting with the vertical axis thereof, to provide a movable inter-

2

lock between the movable seat and the fixed base, whereby the seat is positively held against vertical and tilting movements relative to the base.

The path of movement of the movable seat, as controlled by said pivoted links, is such that when the seat is moved from one operative position to another, the vertical axis thereof describes arcs which intersect at a predetermined point. The pivoted link connections function to impart reverse rotation to the seat as its vertical axis passes from one side to the other of said intersection.

When the seat portion is in either of its two normal operative positions, its vertical axis is positioned at one side of the intersection point in the said path of travel. Consequently, the initial lateral movement of the seat to move it outwardly from the wall is coupled with a rotational movement in one direction. As soon as the vertical axis of the seat passes through said point of intersection, the pivoted links function to compel reverse rotation of the seat until the cycle of operation again moves the said vertical axis through said point of intersection. It will be seen, therefore, that movement of the seat from one position to another, involves two reverses in the direction of rotation, to-wit: During the initial or releasing movement of the seat from its operative position, it is rotated in one direction, then reversed for the major portion of the cycle and then again reversed during the final or locking movement.

The present invention, therefore, includes as one of its specific objects the provision of a revoluble seat structure, constructed and operating as above described, whereby the final movement of the seat to its operative positions moves one of the pivoted links into a position whereby it cooperates with other parts of the structure, to-wit, the other link and co-engaging stop and abutment surfaces to lock the seat in an operative position.

The invention is illustrated in one preferred embodiment in the accompanying drawings wherein:

Fig. 1 is a side view of a railway car seat constructed in accordance with this invention.

Fig. 2 is a plan view on a reduced scale of the seat shown in Fig. 1.

Figs. 3, 4, 5 and 6 show the various positions assumed by the seat when reversing it from the position shown in Fig. 2 to the position shown in Fig. 6.

Fig. 7 is a plan view of the seat supporting frame showing the position of the frame rela-

tive to the base when the seat is in the position indicated in Fig. 2.

Fig. 8 is a fragmentary view illustrating the relative position of the parts for effecting the interlock between the seat and the base when the seat is in the position shown in Fig. 7.

Fig. 9 is a view similar to Fig. 7 but illustrating the seat frame and associated parts in the position which it assumes during the initial or releasing movement of the seat from its locked position.

Fig. 10 is a view similar to Fig. 9 but showing the seat supporting frame in a position which it assumes when the seat is in the position indicated in Fig. 13.

Fig. 11 is a fragmentary plan view illustrating the position of the links and associated elements when the parts are in the position indicated in Fig. 10.

Fig. 12 is a vertical section through the fixed base and the seat supporting frame, the section being taken on line 12-12 of Fig. 7.

Fig. 13 is a plan view similar to Fig. 9 but illustrating the position assumed by the parts immediately prior to the movement of the seat into the position shown in Fig. 6; and

Fig. 14 is a view showing the position of the parts when the seat is in the said position indicated in Fig. 6.

Referring first to Figs. 1 to 6, inclusive:

The seat is illustrated in the form of a double passenger car seat with one side face of the seat arranged in close relation to a side wall 10 of the car. It is composed generally of a base member 11 adapted to be fixed to the floor and a revoluble seat portion 12 supported on the base. The seat portion 12 includes a rectangular frame 13 which seats on the upper surface of the base. Preferably, the weight of the frame is such as to minimize friction between the frame and base and the width of the frame is such as to provide a firm non-tilting support on the base 11. The frame 13 is movably attached to the base 11 by means of a pair of reversing links 14 and 15. The said links are pivoted at their remote ends 16-17, respectively, to a reinforcing web 18 extending across the base so as to swing in a horizontal plane. The swinging ends of the links are pivotally connected at 19 and 20 to arms 21-22 of a cross-beam 23 extending from side to side of the frame 13. Preferably the said adjacent ends of the links are attached to the said beam 23 at locations relatively close to axis 24 of the rotating seat. The effective length of each link is greater than one-half the distance between the pivots 16-17. It will be seen, therefore, that when the revoluble seat portion is in the position shown in Fig. 9, the vertical axis 24 of the seat is positioned at the intersection of a line 25 passing through the fixed pivots 16-17 and a line 25a passing through the movable pivots 19 and 20. The particular arrangement of the said links 14-15 so control the path of movement that the vertical axis of the seat will follow a predetermined path. In order to provide a movable interlocking connection between the base and the movable seat portion, the web 18 of the base is formed with an opening 26, the edges of which correspond to the contour of the path of movement indicated by broken line 27, which is followed by the vertical axis 24 of the seat. A stud 28, coinciding with the said axis 24, has rolling contact with the edge of opening 26 and is formed with a head portion 29 which projects beneath the web 18 of the base along the margins of the opening 26 so as to

prevent all vertical and tilting movements of the seat relative to the base.

When the seat is in one fixed position, a stop surface on a moving part of the structure, for example the outer surface of the stud 28, engages an abutment positioned on the base, for example the edge surface of one of the recesses 30-31 of said opening 26. Each recess 30-31 is positioned at one side of the intersection of the said path of travel and is preferably of the same diameter as the stud 28 so that a close fit is provided for approximately half the diameter of the stud. In assuming the position shown in Figs. 7 and 8, the vertical axis 24 (Fig. 9) crosses the intersection of the path of travel 27. Consequently, the links 14 and 15 assume positions in which their longitudinal centers have moved from the parallel alignment shown in Fig. 9 to the angular position shown in Fig. 7, whereby the angularity of the links relative to the line 25 and to each other is such as to prevent the seat from being released by pressure applied thereto in the direction of the arrow indicated at A in Fig. 7. When it is desired to release the seat from the above locked position, a pulling force is applied in the direction of the aisle, as indicated by arrow B in Fig. 7. During the application of this force, the curvature of the recess 30 of the opening 26 reacts against the stud 28 so as to serve as a can to force the pivoted link 14 from the position indicated in Fig. 7 to the position shown in Fig. 9, that is to say, a rotational movement is imparted to the seat whereby the line 25a passing through the moveable pivots 20-21 assumes a position at right angles to the line 25 passing through the fixed pivots 16-17. From this position the rotational movement of the frame can then be reversed to follow the direction indicated by the arrows in Figs. 3, 4, 5 and 9 to the position indicated in Fig. 6.

When the reversing movement of the seat carries it to the position indicated in Fig. 6, the stud 28 moves into the recess 31 of the opening 26 so as to abut against the edges thereof and lock the seat in this position. In assuming this position of the seat, the links 14 and 15, as previously described, assume positions in which their longitudinal centers are moved out of the parallel alignment of Fig. 13 to the angular positions shown in Fig. 14, whereby the angularity of the links 14 and 15 relative to line 25 and to each other is such that they will resist turning of the seat when applied against the side of the seat in the direction indicated by arrow C in Fig. 14. It will be seen that during part of the movement of the frame 12 from the position indicated in Fig. 2 to the position indicated in Fig. 6, the link 14 takes the lead for the entire movement. However, in reversing the seat from the position indicated in Fig. 14, the link 15 would lead in the entire movement.

This application is a continuation of my co-pending application Serial 512,692, filed December 3, 1943 (abandoned December 6, 1946).

65 I claim:

1. In a reversible seat structure, a base member, a seat member revoluble about a vertical axis and slidably supported on said base member and adapted during the reversing movement to follow a curved path, the opposite end portions of which intersect at a common point, means for controlling said path of movement comprising a pair of links arranged in overlapped relation and having their overlapped ends pivotally attached to the seat member at opposite sides of said ver-

tical axis at equal distances therefrom and on a line passing therethrough and having their remote ends pivotally attached to the base at opposite sides of said intersection in said path of travel at equal distances therefrom and on a line passing therethrough, a trackway on the base conforming in contour to said path of travel, a stud depending from the seat member in axial alignment with the said vertical axis of the seat member and arranged to engage the said trackway, there being a head on said stud which projects beneath said trackway for preventing vertical and tilting movements of the seat member relative to the base.

2. In a reversible seat structure, a base member, a seat member revoluble about a vertical axis and slidably supported on said base member and adapted during the reversing movement to follow a curved path, the opposite end portions of which intersect at a common point, means for controlling said path of movement comprising a pair of links arranged in overlapped relation and having their overlapped ends pivotally attached to the seat member at opposite sides of said vertical axis at equal distances therefrom and on a line passing therethrough and having their remote ends pivotally attached to the base at opposite sides of said intersection in said path of travel at equal distances therefrom and on a line passing therethrough, the said base being formed with a web having an opening therein, the edge of which provides a trackway conforming in contour to said path of travel, a stud depending from the seat member in axial alignment with said vertical axis of the seat member and arranged to engage the said trackway, there being a head on the said stud which projects beneath said web of the base to prevent vertical and tilting movements of the seat member relative to the base, and the said trackway being formed adjacent the extremities of said path of travel to provide a pocket for receiving said stud and for limiting the movement of the seat member.

3. In a reversible seat structure, a base member, a seat member revoluble about a vertical axis and slidably supported on said base member and adapted during the reversing movement to follow a curved path, the opposite end portions of which intersect at a common point, means for controlling said path of movement comprising a pair of links arranged in overlapped relation and having their overlapped ends pivotally attached to the seat member at opposite sides of said vertical axis at equal distances therefrom and on a line passing therethrough and having their remote ends pivotally attached to the base at opposite sides of said intersection in said path of travel at equal distances therefrom and on a line passing therethrough, a stop surface on a moving part of said structure, and an abutment positioned on the base member for holding engagement with said stop surface only when said

vertical axis of the seat member is positioned intermediate one end portion of the said curved path and the said intersection in said path of travel.

5. In a reversible seat structure, a base member, a seat member revoluble about a vertical axis and slidably supported on said base member and adapted during the reversing movement to follow a curved path, the opposite end portions of which intersect at a common point, means for controlling said path of movement comprising a pair of links arranged in overlapped relation and having their overlapped ends pivotally attached to the seat member at opposite sides of said vertical axis at equal distances therefrom and on a line passing therethrough, abutment means on the base member at one side of the intersection in said path of travel, and a stop having a fixed relation to said vertical axis and moveable by movement of the seat member, into engagement with said abutment means when said axis moves to a position intermediate said abutment means and the intersection in said path of travel.
5. In a reversible seat structure, a base member, a seat member revoluble about a vertical axis and slidably supported on said base member and adapted during the reversing movement to follow a curved path, the opposite end portions of which intersect at a common point, means for controlling said path of movement comprising a pair of links arranged in overlapped relation and having their overlapped ends pivotally attached to the seat member at opposite sides of said vertical axis at equal distances therefrom and on a line passing therethrough and having their remote ends pivotally attached to the base at opposite sides of said intersection in said path of travel at equal distances therefrom and on a line passing therethrough, abutment means on the base at one side of said intersection, and a stud on the seat member in a fixed position relative to said vertical axis and moveable, by the movement of the seat member into engagement with said abutment means only when said axis moves to a position intermediate said abutment means and the said intersection in said path of travel.
